FRANCISCO, CALIFORNIA.

SAFETY-LOCK FOR ELEVATOR-DOORS.

1,295,444.

Specification of Letters Patent.

Patented Feb. 25, 1919.

Application filed June 27, 1917. Serial No. 177,283.

To all whom it may concern:

Be it known that I, WALLACE E. DAY, a citizen of the United States, residing at Oakland, in the county of Alameda and State of California, have invented new and useful Improvements in Safety-Locks for Elevator-Doors, of which the following is a specification.

This invention relates to the type of safety lock for elevator doors which is held against release until the car comes to a full stop opposite the door. In most of the prior devices this result is attained by means of a guard released by means of a cam carried by the car, said cam being normally retracted out of the path of the guard but by means of complicated electrical mechanism projectable into the path of said guard when the car stops opposite the door.

My object is to simplify and improve the construction and operation of the releasing mechanism for the guard. While I use a cam carried, preferably, on the car and co-operating with guard-releasing mechanism, it is not a receding cam but a simple fixed obstruction at all times projected into the path of the releasing mechanism, and in order that, when the car is passing a door but not destined to stop opposite it, the guard may not be released, I provide a simple electromagnet to hold the lock guard in place, notwithstanding the fact that the usual cam-operated releasing means has been actuated. The electromagnet has its circuit closed through the main operating circuit for the elevator so that only when the operating circuit is broken and the car is standing in position opposite the door, can the lock be operated.

One form which my invention may assume is exemplified in the following description and illustrated in the accompanying drawings, in which—

Figure 1 shows a side elevation of the lock casing, with the cover removed.

Fig. 2 shows an end elevation of the same.

Fig. 3 is a view in diagram, illustrating the wiring arrangement of the elevator controller and the manner in which the movement of the controller lever establishes a circuit through the lock magnet.

Referring more in detail to the drawings, I show a casing 10 which is fitted in place on the door frame and contains the entire

lock mechanism, which comprises a pivoted dog 11 forming a guard for a latch 12, the latter carried by the door and having a hook-shaped end to enter the casing. Said dog has a right-angular extension rigidly formed thereon and carrying an armature 13 co-operating with an electromagnet 14. Pivoted coaxially with the pawl 11 is a rod 15 to which is fixed at its inner end a crank arm 16 overlying the armature and at its outer end, on the exterior of the casing, a weighted arm 17, which is fitted at its end with a roller 18 to engage and co-operate with a cam track 19 on the car or cage of the elevator. The dog 11 and its integrally formed armature are loosely mounted upon the shaft 15 between bearing extensions of the crank arm 16. The magnet is connected in series with the main operating circuit of the elevator preferably through the controller and direction switches not shown. Normally the pawl is held in locking engagement with the latch by the action of a weighted arm. When the magnet is energized, the armature is pulled down and the pawl held out to overlie the latch and retain the latter in locked position. A spring 20 acts on the pawl to retract it and maintain it out of engagement with the latch when the weight of arm 17 is relieved therefrom and the magnet 14 is deenergized. Normally, the weighted arm 17 causes the crank arm 16 to press down on the armature 13 and thereby retain the pawl 11 in position to act as a guard independent of the action of the magnet.

In operation, when the car is near a door equipped with this lock, the cam 19 engages the roller 18 and moves the weighted arm to one side, thereby raising the crank arm 16 and taking the pressure off the armature 13 and but for the magnet 14 the pawl 11 might be moved away from guard position under the influence of the spring 20. However, unless the car stops and the main operating circuit in which the magnet 14 is included becomes broken, thus demagnetizing the magnet, this will not happen and the door cannot be unlatched. At other times when the operating circuit is broken, as when the car is standing still at other points than the landings, then the weighted arm serves to retain the pawl in guard position. Unlatching can be accomplished only when the car is opposite the door and standing

still with the main operating circuit broken, at which time both the cam 19 and the de-energized magnet 14 are in condition to release the said pawl.

5 I also provide the usual door switch so that when a door is open the car cannot be operated. This may comprise spaced terminals 21 and 22 with which a contact plate 23 co-operates to form an electrical connection across, said plate being yieldingly mounted upon and movable with a weighted lever 24 and held in contacting engagement with said terminals by means of the latch hook 12. When the latch hook is released 10 the weighted arm lifts the contact plate out of engagement with the terminals and breaks the circuit. The terminals 21 and 22 of all of the lock mechanisms are connected in series with an operating or controlling 15 circuit for the elevator and must be closed 20 before the car will operate.

Various changes in the construction and arrangement of the several parts herein shown and described may be employed without departing from the spirit of my invention 25 as disclosed in the appended claims.

It will be seen that before the car can be operated the door must be closed and locked. This is so because the complete closing and 30 latching of the door is necessary to close the switch terminals 22-23, and the first effect of actuating the starting button of the controlling circuit is to energize the magnet 14 and thereby move the pawl 11 into place 35 above the latch. Without the magnet 14 the door would remain unlocked until the roller 18 had left the cam 19, which ordinarily would not occur until the car was a foot or so above or below the landing.

40 Having thus described my invention, what I claim and desire to secure by Letters Patent is—

1. A safety lock for elevator shaft doors comprising a lock case fixed to the door frames and having a bolt opening through the side wall thereof, a latch bolt carried by the door and adapted to move horizontally therewith to be projected through the opening in the case and to positively engage the 45 wall thereof, a pivoted detent mounted within the case and above the bolt, gravity means for normally holding said detent in a position to prevent the bolt from moving from engagement with the case, positive means carried by the elevator for releasing said gravity means whereby said detent may be allowed to swing out of engagement with the bolt, a main controller, an electric controller circuit, an electromagnet within the case, an 50 electric circuit for said magnet adapted to be closed by movement of the controller arm, means actuated by the bolt upon its entrance to and engagement with the case to establish said electric controller circuit, and separate means controlled by the magnet for

swinging the detent into an obstructing position above the bolt irrespective of its other operating member.

2. An elevator door lock comprising a lock case, an electric switch member within 70 said case, gravity means for normally holding said switch open, an electromagnet inclosed within the case, an electric circuit including the magnet, a latch bolt adapted to be projected through the opening in the 75 wall of the case to engage the same and to close said switch, a pivoted detent disposed above said bolt and positioned within the case, gravity means for normally holding the detent in an obstructing position above 80 the bolt, a spring member opposing said gravity means, positive means carried by an elevator car to swing the gravity means from its holding position when the car is in register with the doorway of the elevator shaft, 85 and a separate member adapted to be controlled by the electromagnet to swing the detent into an obstructing relation to the bolt when the magnet circuit is closed.

3. An elevator lock comprising a case, a 90 lock bolt adapted to project into and engage the side wall of said case, a pivoted detent within the case, a spring normally acting to hold the detent out of engagement with the lock bolt, gravity means opposing 95 said spring and normally holding the detent in an obstructing position above said latch bolt, positively operated means carried by an elevator car whereby the weight upon the detent may be relieved to allow it 100 to swing from above the bolt, a switch adapted to be closed by the presence of the bolt within the case, a magnet disposed in relation to the detent to influence it when energized, and an electric circuit including 105 said magnet and adapted to be controlled by the movement of the main controller of the elevator, whereby the detent may be independently operated to swing into a locking 110 position.

4. A safety lock for elevator shaft doors comprising a lock case having a bolt opening through the side wall thereof, a latch bolt adapted to be projected into said case and to positively engage the wall thereof, a 115 lever shaft disposed transversely of the case and above the bolt, a bell-crank freely mounted upon said shaft and disposed with one of its arms extending downwardly in an obstructing position above the lock bolt, a spring normally holding said arm out of engagement with the lock bolt, an electromagnet disposed in position to influence the opposite arm of the bell-crank to swing the first-named arm into its obstructing position 120 above the bolt, gravity operated means fixed to said shaft and adapted to normally hold the bell crank in its obstructing position, a switch closed by the presence of the lock bolt within the case whereby the circuit through 125 130

an elevator controller circuit may be completed, and means carried by the elevator car to relieve the bell-crank from the pressure of the gravity means independently of the action of the electromagnet.

5. A lock for elevator doors comprising a case having an opening through the side wall thereof, a latch bolt carried by the door and adapted to be projected into and to positively engage the case, a detent within the case, a pivot shaft extending transversely of the case and supporting the detent above the lock bolt and in a position to obstruct the removal of said bolt from the case,

10 a spring acting to normally hold said detent out of an obstructing position, an armature formed integral with said detent and extending in a substantially horizontal plane, an electromagnet disposed beneath the armature to influence it in a downward direction, a crank arm fixed to the pivot shaft independently of the detent and armature, a counterweight arm fixed to said shaft exteriorly of the case and adapted to exert a downward pressure upon the armature by the crank arm, a roller upon the end of said counterweight arm, a cam member carried by the elevator car and adapted to engage the roller to relieve the weight of the counterweight from the top of the armature, a controller circuit switch adapted to be closed by the presence of the lock bolt within the case, and a separate electric circuit including the magnet whereby the movement

of the controller of the car to close its circuit will cause the detent to be swung outwardly by the action of the magnet to prevent the removal of the bolt from the case irrespective of the action of the counterweight arm.

6. An elevator door lock comprising a lock case, an electric switch member within said case, gravity means for normally holding said switch open, an electromagnet, an electric circuit including the magnet, a latch bolt adapted to be projected through an opening in the wall of the lock case to engage the same and to close said switch, a pivoted detent disposed above said bolt, gravity means for normally holding the detent in an obstructing position above the bolt, a yieldable member opposing said gravity means, positive means carried by an elevator car to swing the gravity means from its holding position when the car is in register with the doorway of an elevator shaft, and means adapted to be controlled by the electro-magnet to swing the detent into obstructing relation to the bolt when the magnet circuit is closed.

In testimony whereof I have hereunto set my hand in the presence of two subscribing witnesses.
